UNITED STATES PATENT OFFICE.

FRANK E. KAPP, OF TIDIOUTE, PENNSYLVANIA.

CARBURETER.

1,187,996

Specification of Letters Patent. Patented June 20, 1916.

Application filed May 1, 1915. Serial No. 25,191.

To all whom it may concern:

Be it known that I, FRANK E. KAPP, a citizen of the United States, residing at Tidioute, in the county of Warren and State of Pennsylvania, have invented certain new and useful Improvements in Carbureters; and I do hereby declare the following to be a full, clear, and exact description of the invention, such as will enable others skilled in the art to which it appertains to make and use the same.

This invention relates to carbureters, and has for its primary object to provide a device of this character embodying a novel and efficient connection between the air and liquid fuel controlling valves, affording maximum adjustability and permitting a wide range in the proportion of air and gas.

With these and other objects in view, the invention consists in the novel construction, arrangement and formation of parts as will be hereinafter specifically described, claimed and illustrated in the accompanying drawing, in which:

25 Figure 1 represents a longitudinal sectional view through the improved carbureter, and Fig. 2 represents a fragmental detail view in perspective, of the adjustable connection between the air and liquid fuel controlling valves.

Referring to the drawing in detail, wherein similar reference numerals designate corresponding parts throughout the several views, the numeral 5 indicates generally the body of the carbureter which includes an air intake port 6, outlet port 7 and a carbureting chamber 8. An air controlling valve 9 is arranged in the air inlet port 6 and a throttle valve 10 is arranged in the outlet port 7. A float chamber 11 is arranged laterally of the body of the carbureter and contains a float 12 which is connected with a valve 13 for controlling the flow of liquid fuel through the fuel pipe 14. A spray nozzle 15 and pipe 16 communicate the lower portion of the float chamber 11 with the carbureting chamber 8.

A needle valve 17 is provided for controlling the flow of liquid fuel through the nozzle 15 and the stem 18 of said valve is slidably mounted in an externally screwthreaded plug 19 secured in the body of the carbureter directly above the open end of the spray nozzle 15. A horizontally disposed air intake valve 20 is provided with oppositely directed stems 21 and 22 slidably mounted in the plug

23 and bottom of the body of the carbureter, respectively. The valve 20 is normally retained in closed position by the tension of a spring 24 coiled about the lower stem 22 and engaged between the valve 20 and the bottom of the body 5. A valve seat 25 is secured in the carbureter body and is adapted to cooperate with the valve 20. A ring 26 is secured to the upper portion of the carbureter body, under the head of the externally screwthreaded plug 19 and is provided with an integral radially directed arm 27 constituting a guide and support for the relatively adjustable arm 28, having an integral sleeve 29 slidably receiving the guide arm 27. The sleeve 29 and arm 28 are adapted to be secured in adjusted position longitudinally of the guide arm 27 by a set screw 30, and the upper free end of the adjustable arm 28 is pivotally secured by a pin 31 between the parallel ears 32 of a sleeve 33, slidably mounted upon the connecting rod 34 and adapted to be secured in adjusted position by a set screw 35 or equivalent means. 75

One end of the connecting rod 34 is slidably received within an aperture 36 formed adjacent the upper terminal of the enlarged end 37 of the stem 18 of the fuel controlling valve 17. The opposite extremity of the connecting rod 34 is movable longitudinally through a transverse aperture 38 formed in the enlarged upper end 39 of the upper valve stem 21 of the air controlling valve 20. The transverse opening 38 communicates with a longitudinal recess 40 formed in the enlarged end 39 of the valve stem 21 and the upper extremity of the side wall of said recess is internally screwthreaded to fit a set screw 42 having a head 43, whereby the screw may be conveniently adjusted. The adjacent extremity of the connecting rod 34 is normally retained in engagement with the rounded end of the set screw 42 by the tension of a spring 44 positioned within the recess 40 and engaged with the under surface of the connecting rod 34. 85

In operation, the outlet port 7 of the carbureter is connected with the intake manifold or pipe of the internal combustion engine (not shown) and during the suction stroke of the piston the suction created within the carbureter body automatically opens the valve 20, and the opening movement of said valve is transmitted to the needle valve 17 through the stem 21, connecting rod 34 and valve stem 18, the connecting rod 34

swinging upon the pivot pin 31 lifts the valve stem 18 and needle valve 17, thus opening the latter. By properly adjusting the sleeves 33 and 29 longitudinally of the 5 connecting rod 34 and relatively stationary guide arm 27, respectively, the relative movement of the valves 17 and 20 may be varied to produce the desired proportion of air and liquid fuel. By adjusting the screw 42 10 the normal position of the needle valve 17 relative to the mouth of the spray nozzle 15 may be varied, as desired.

What I claim is:

In a carbureter, a body, air and liquid 15 fuel controlling valves arranged in said body, valve stems carried by said valves having apertured ends, a rod pivotally mounted in the apertures of said stems, an arm ad-

justably secured to said body, a sleeve adjustable longitudinally of said rod, means 20 for securing said sleeve in adjusted position on said rod, a second arm adjustable longitudinally of the first-mentioned arm, a pivotal connection between the second arm and said adjustable sleeve, a fulcrum screw adjustably fitted in the stem of the air valve having a rounded end engaging said rod, and resilient means normally retaining said connecting rod in engagement with said screw. 25 30

In testimony whereof I affix my signature in presence of two witnesses.

FRANK E. KAPP.
